UNITED STATES PATENT OFFICE.

THOMAS B. LASHAR, OF BRIDGEPORT, CONNECTICUT, ASSIGNOR TO INTERNATIONAL SILVER COMPANY, OF BRIDGEPORT, CONNECTICUT, A CORPORATION OF NEW JERSEY.

DESIGN FOR A HANDLE FOR SPOONS, FORKS, OR SIMILAR ARTICLES.

40,933.

Specification for Design.

Patented Oct. 11, 1910.

Application filed March 11, 1910. Serial No. 548,751. Term of patent 7 years.

To all whom it may concern:

Be it known that I, THOMAS B. LASHAR, a citizen of the United States, residing at Bridgeport, county of Fairfield, State of Connecticut, have invented a new, original, and ornamental Design for Handles for Spoons, Forks, or Similar Articles, of which the following is a specification, reference being had to the accompanying drawing, forming part thereof.

The drawing is a representation of a spoon embodying my novel design, with the outline of a fork indicated by dotted lines.

The essential feature of my design is that the handle 10 is very narrow where it joins the bowl 11 and for approximately one half of its length from said bowl is gradually widened by a very slight taper until the point 12 is reached, the narrow portion of

the handle being ornamented with a bride rose as indicated at 13. The sides of the handle above point 12 are curved to form the swell or widened portion 14 which is also ornamented with a bunch of bride roses, as indicated at 15. The end of the handle is widened as indicated at 16 and the edges converge to form a point 17, a group of three bride roses being arranged on said end in triangular relation. The three groups of roses are connected by scroll lines to form a continuous scheme of ornamentation.

What I claim is:—

The ornamental design for a handle for spoons, forks or similar articles, as shown.

THOMAS B. LASHAR.
